UNITED STATES PATENT OFFICE

2,467,119

FLANGE OILER

Frank William Edwards, Chicago, Ill., assignor to
 The Ohio Injector Company of Illinois, Chi-
 cago, Ill., a corporation of Illinois

Application June 10, 1947, Serial No. 753,772

5 Claims. (Cl. 184—3)

1

This invention relates to oilers for the flanges of the wheels of railway vehicles, and it has particular reference to a flange oiler the design and mounting of which with respect to the wheel it serves, especially a wheel of a locomotive, provide for marked flexibility of movement to accommodate it to movement of such wheel, whether a right-hand or a left-hand wheel, and which includes also an improved means for delivering oil to the wheel flange.

One object of the invention is to provide a flange oiler of simple, rugged and relatively economical construction, the parts of which may readily be replaced or repaired when they have become worn or otherwise unserviceable.

Another object is to provide a flange oiler the wheel-flange engaging oiler shoe of which is so symmetrically designed as to be adapted for use with either a right-hand or a left-hand wheel installation, and capable of being easily adjusted in its mounting means with respect to the wheel.

A further object is to provide mounting means for the oiler shoe so constructed and assembled with respect to the railway vehicle and the wheel serviced as to permit movement of the shoe with the wheel flange axially, radially and axially-angularly with the wheel.

A still further object is to provide means for conducting oil through the shoe to the wheel flange in such a manner that the likelihood of stoppage of its flow is reduced to a minimum.

In the accompanying drawings illustrating the invention, in the several figures of which like parts are similarly designated,

Fig. 1 is a side elevation illustrating the flange oiler of the invention in association with a wheel, and showing part of mounting bracket in section,

Fig. 2 is a perspective view of the flange oiler, Fig. 3 is a front view of the flange oiler with a portion of the wheel with which it is associated shown in section,

Fig. 4 is a top plan view of the flange oiler with the mounting bolts omitted,

Fig. 5 is an enlarged axial sectional view of the oiler shoe in association with a wheel, and

Fig. 6 is a perspective view of the oiler shoe detached.

In the preferred embodiment illustrated, the flange oiler includes a mounting plate 1 with a pair of marginal guide strips 2 secured thereto in offset spaced relation by end and intermediate bolts 3 and 4, respectively, with interposed spacing collars 5 and 6 and lock washers 7 where desired. The intermediate bolts 4 serve not only

2

to complement the end bolts 3 in affixing the strips 2 to the mounting plate 1 but furnish a means for attaching the flange oiler as a whole to the mounting bracket 8, Fig. 1.

5 Positioned between the mounting plate 1 and the strips 2, and capable of limited sliding movement therebetween vertically, laterally and angularly, is a slide plate 9 having laterally off-standing pairs of guide arms 10 which extend between adjacent portions of the mounting plate 1 and the guide strips 2 and serve not only to retain the slide plate in position but to limit its movement relatively to the spacing collars 5 and 6. Adjacent to its lower end the slide plate 9 is 15 provided with a bearing member 11 having a recess 12 to closely engage the shank 13 of the oiler shoe 14, and laterally extending bolting flanges 15 to which the oiler shoe is secured by bolts 16 which pass through ears 17 on the oiler shoe shank 13 and are preferably provided with lock washers 18.

By this arrangement it will be seen that the oiler shoe may readily be removed and restored or replaced and, due to the symmetrical arrangement of the bolting ears 17 with respect to the axis of the shank 13, may be properly positioned for either right-hand or left-hand operation.

Moreover, the provision for vertical, lateral and angular movement of the slide plate 9, and with 30 it of the oiler shoe 14, makes possible accommodation of the shoe to radial, axial and axially-angular motion of the wheel 19 with the flange 20 of which the shoe is engaged.

As shown particularly in Fig. 5, the operative 35 face of the oiler shoe is provided with a recess 21 substantially conforming in contour to the wheel flange 20 and flanked by guide yokes 22 and 23 at front and rear of the flange, respectively, the yoke 23 at the rear of the flange being made to 40 extend well down radially of the wheel in order to guard against displacement of the shoe from the flange during movement of the wheel.

45 Interiorly of the oiler shoe 14 and its shank 13 extends a bore 24 (Fig. 5) terminating at one end in the wheel flange engaging recess 21 and at its other end in a threaded socket 25 to receive the end of a suitable flexible or jointed oil conduit 26.

Within the bore 24 is arranged a tubular feed member 27 of less external diameter than the 50 internal diameter of the bore 24 with its lower end cut off at an angle in a plane tangent to the adjacent face of the wheel flange. During operation of the oiler this end of the tubular feed member will wear so as to substantially conform 55 to the face of the wheel flange, but it will be

suspended in circumferentially spaced relation to the wall of the bore 24 and will be prevented from dropping out of the bore by a cross pin 28 or the like the projecting ends of which are normally spaced from but may bear upon the shouldered inner extremity 29 of the threaded socket 25. Obviously, with this mode of assembly, the feed member 27 is permitted a limited movement within the bore 24.

This tubular feed member 27 has advantages over the solid rod type of feed members sometimes used in installations of this general character for the reason that oil from the conduit 26 may pass not only along its outer surface and along the wall of the bore, or between these surfaces, but may pass also through or along the walls of its central tubular passage, thus guarding more effectively against clogging, it being understood that oil is ordinarily fed through the conduit 26 to the oiler shoe in small measured quantities and usually drop by drop.

From the foregoing it will be apparent that the flange oiler of the invention has advantages over devices of a similar nature now known, for the reason that the oiler shoe can bodily follow the wheel flange as the wheel moves. In other words, it can shift bodily vertically and laterally and can move angularly also, whereas with similar devices now known provision is made only for vertical and angular movement, and lateral movement must be accommodated by the provision for angular movement.

Also, the provision of the improved feeding means, embodied in the tubular feed member 27, constitutes a marked advantage over present known devices.

Various changes and modifications are considered to be within the principle of the invention and the scope of the following claims.

What I claim is:

1. A flange oiler for the flange of a vehicle wheel, including mounting means attachable to a part of the vehicle and with respect to which the wheel is movable vertically, laterally and angularly, and slide means carrying an oiler shoe cooperating with the wheel flange and associated with said mounting means and capable of movement with respect thereto to accommodate said shoe to the movements of the wheel, said mounting means including a mounting plate and guide strips affixed to said plate adjacent to its lateral edges and spaced from the face of said plate, and said

slide means comprising a slide plate normally in substantial face-to-face relation to said mounting plate and guided by said mounting plate and guide strips, said slide plate being provided with bearing means for detachable connection of said oiler shoe.

2. A flange oiler as claimed in claim 1, in which the detachable connection means for said oiler shoe include a bearing member on said slide plate and means for securing said oiler shoe in fixed relation to said bearing means comprising members symmetrically arranged with respect to said oiler shoe and admitting of its attachment to said bearing member in either of two positions for cooperative functioning with a right-hand or left-hand wheel flange.

3. An oiler for the flange of a vehicle wheel, including a mounting plate, guide strips secured adjacent to the lateral edges of said mounting plate and spaced therefrom, a slide plate having laterally offstanding guide arms interposed in the space between said mounting plate and guide strips and serving to hold said slide plate in cooperative relation to said mounting plate for limited movement vertically, laterally and angularly with respect thereto, and a flange oiler shoe carried by said slide plate and movable therewith in response to movement of the wheel with which it cooperates.

4. A flange oiler as claimed in claim 3, in which the guide strips are secured to the mounting plate by bolts serving also to limit relative movement of said slide plate and mounting plate.

5. A flange oiler as claimed in claim 3, in which the slide plate is of less width than the distance laterally of said mounting plate between said guide strips, and said guide arms serve to maintain sliding relation between said guide plate and mounting plate.
